MAIL BOX

George Grafton, Jr., Kent, Ohio

Application September 9, 1957, Serial No. 47,665

Term of patent 3½ years

(Cl. D74—9)

Fig. 1 is a front perspective view of a mail box showing my new design; and

Fig. 2 is an end elevational view thereof taken from the left side of Fig. 1.

The right side of the mail box presents a substantially similar appearance to that shown in Fig. 2, and the back of the mail box is substantially plain and unornamented.

I claim:

The ornamental design for a mail box, substantially as shown and described.
